JOSEPH L. BATES, OF BOSTON, MASSACHUSETTS.

Design No. 2,743, dated August 13, 1867.

DESIGN FOR A TRADE-MARK.

The Schedule referred to in these Letters Patent and making part of the same.

TO ALL PERSONS TO WHOM THESE PRESENTS SHALL COME:

Be it known that I, JOSEPH L. BATES, of Boston, in the county of Suffolk, and State of Massachusetts, have invented or produced a new ornamental Design for a Trade-Mark; and do hereby declare the same to be fully described in the following specification, and represented in the accompanying drawing.

The said trade-mark consists of the representation of a shield provided with a double border surrounding a stereoscope placed in the middle of the shield, the whole being substantially as exhibited in the drawing, in which A is the shield, a a' the double border, and b the stereoscope.

I claim the said design as of my invention or production.

JOSEPH L. BATES.
